US00D780505S

(12) **United States Design Patent** (10) **Patent No.:** **US D780,505 S**
Gamble et al. (45) **Date of Patent:** **** Mar. 7, 2017**

(54) **FOOD WASTE DISPOSER**

(71) Applicant: **Emerson Electric Co.**, St. Louis, MO (US)

(72) Inventors: **Kelly T. Gamble**, Waterford, WI (US); **Deborah R. Groshek**, Kenosha, WI (US); **Eric J. Schultz**, Thiensville, WI (US); **Randall E. Hammer**, Muskego, WI (US); **Grey B. Parker**, West Bloomfield, MI (US); **Josiah J. Lacolla**, Farmington Hills, MI (US)

(73) Assignee: **Emerson Electric Co.**, St. Louis, MO (US)

(**) Term: **15 Years**

(21) Appl. No.: **29/556,615**

(22) Filed: **Mar. 2, 2016**

Related U.S. Application Data

(62) Division of application No. 29/514,363, filed on Jan. 12, 2015, now Pat. No. Des. 759,423.

(57) **CLAIM**

The ornamental design for a food waste disposer, as shown and described.

DESCRIPTION

FIG. 1 is a perspective view of a food waste disposer embodying our new design;

FIG. 2 is a front elevational view of the food waste disposer of FIG. 1;

FIG. 3 is a rear elevational view of the food waste disposer of FIG. 1;

FIG. 4 is a top plan view of the food waste disposer of FIG. 1;

FIG. 5 is a bottom plan view of the food waste disposer of FIG. 1;

FIG. 6 is a left elevational view of the food waste disposer of FIG. 1; and,

FIG. 7 is a right elevational view of the food waste disposer of FIG. 1.

In FIGS. 1-7, the broken lines in all views are for the purpose of illustration and are not part of the claimed design.

1 Claim, 5 Drawing Sheets
